UNITED STATES PATENT OFFICE.

IRVINE JAMES ADAIR, OF DALLAS, TEXAS, ASSIGNOR OF ONE-THIRD TO
EDWARD J. GANNON, OF SAME PLACE.

BOOK-ADJUSTER.

SPECIFICATION forming part of Letters Patent No. 357,543, dated February 8, 1887.

Application filed September 2, 1886. Serial No. 212,566. (No model.)

To all whom it may concern:

Be it known that I, IRVINE JAMES ADAIR, of Dallas, in the county of Dallas and State of Texas, have invented a new and useful Improvement in Book-Adjusters, of which the following is a specification.

My invention consists in a book-adjuster for leveling books, especially large heavy account-books—such as are used by book-keepers, &c.—and also for holding the leaves open and enabling the book to be closed at any time and opened again at the same place without any delay or trouble.

My improved book-adjuster will be herein-after fully described and claimed.

Referring to the accompanying drawings, Figure 1 is a perspective view showing my improved book-adjuster arranged in its operative position; and Fig. 2 is a vertical sectional view taken on line *x x*, Fig. 1, of the drawings. Fig. 3 is a view of a holder made in a single piece.

The same letters of reference indicate corresponding parts in all the figures.

Referring to the several parts by letter, A indicates the circular base-piece, which of course may be made of any other form, and B represents the adjusting-screw, the lower end of which is swiveled in the base-piece A, as shown, so that the screw may be turned freely without disturbing the base-piece, while the upper end of the adjusting-screw is formed with the head B', of sufficient size to form a convenient hold for the fingers in manipulating the screw.

C indicate two rectangular leaves or plates, of wood or other material and of the requisite size, between the rear longitudinal edges of which is secured a strip, D, of suitable thickness, thus forming a rectangular block or plate having the deep longitudinal horizontal recess E; or the holder, instead of being constructed as above described, may be made of a single piece of suitable material, formed with the deep groove or recess E. The holder is formed, near its rear edge, with the vertical screw-threaded aperture F, in which the adjusting-screw works.

G is a V-shaped spring-catch, which has the ends of its parallel arms coiled, as at g, and secured to the outer edge of the holder, so that the cross-bar of the catch will bear on the leaves, as shown in the drawings.

In operation the base A rests on the desk or table to one side of the book, and when the book is opened the cover of that side of it on which the least number of leaves are opened (the left-hand side of the book in Fig. 1 of the drawings) is inserted in the deep horizontal groove or recess E of the holder, and the leaves on that side of the book opened on the upper side of the holder, as shown in Fig. 1 of the drawings, and the free ends of the spring-catch G placed on the leaves, thereby holding the leaves in place, and preventing the wind from blowing them over and thus losing the place, also holding the leaves flat and firmly in place while being written on, and also enabling the book to be closed when through with at the time, and then opened again at the right place without any trouble or delay. The leaves and cover being thus secured, the adjusting-screw is turned, thus raising or lowering the holder, as required, until the two halves or sides of the open book lie perfectly level, as clearly shown in Fig. 1 of the drawings.

From the foregoing description, taken in connection with the accompanying drawings, the construction, operation, and advantages of my book-adjuster will be readily understood.

I am aware that a book-adjuster has been formed of a base, a vertically-adjustable toothed standard thereon, a platform on the upper end of the standard, and a U-shaped wire coiled to form springs and secured at its ends to the under side of the platform, and I do not claim the same, broadly, as of my invention.

Having thus described my invention, what I claim, and desire to secure by Letters Patent, is—

1. The combination, with the holder having the horizontal longitudinal recess and the vertical screw-threaded aperture, of the base-piece and the adjusting-screw swiveled at its

lower end in the said base-piece, as and for the purpose herein set forth.

2. The combination, with the holder having the horizontal longitudinal recess and the vertical screw-threaded aperture, of the base-piece, the adjusting-screw swiveled at its lower end in the said base-piece, and the spring-

catch, arranged as described, as and for the purposes herein set forth.

IRVINE JAMES ADAIR.
